LUMINAIRE

Donald W. Harling, Milwaukee, and Paul J. Curtin, South Milwaukee, Wis., assignors to McGraw-Edison Company, Milwaukee, Wis., a corporation of Delaware

Original design application May 24, 1962, Ser. No. 70,260, now Design Patent 197,438, dated Feb. 2, 1964. Divided and this application Sept. 24, 1963, Ser. No. 76,715

Term of patent 14 years

(Cl. D48—31)

FIG. 1 is a side elevational view of a luminaire embodying our new design;

FIG. 2 is a top plan view thereof; and

FIG. 3 is a bottom plan view thereof.

The characteristic feature of our invention is the illustrated refractor and hood in combination with a conventional base.

This application is a division of our co-pending application Serial No. D. 70,260, now Design Patent 197,438.

We claim:

The ornamental design for a luminaire as shown and described.
